UNITED STATES PATENT OFFICE.

ALBERT C. REE, OF LIBERTYVILLE, ILLINOIS.

SHOCK ABSORBER.

Application filed April 13, 1920. Serial No. 373,635.

To all whom it may concern:

Be it known that I, ALBERT C. REE, a citizen of the United States, and resident of Libertyville, in the county of Lake and State 5 of Illinois, have invented certain new and useful Improvements in Shock Absorbers; and I do hereby declare that the following is a full, clear, and exact description thereof.

This invention relates to shock-absorbers, 10 particularly of the type used in automobiles or the like having spring suspension.

The object of the invention is to provide a shock-absorber that will permit the body of the vehicle to descend freely to a certain 15 distance, but to check the return movement of the same, thereby avoiding the breaking of the vehicle spring or springs at the time when the greatest liability of such breakage occurs.

20 A further object of the invention is to provide means whereby movement of certain parts of the shock-absorber toward each other are severely restrained during the latter part of a long movement, and yet unrestrained on the first part of such movement, as well as on short movements.

In the drawings:—

Figure 1 is a longitudinal vertical section of a shock-absorber, embodying this invention.

30 Figure 2 is a section taken on the line 2—2 of Figure 1, showing a plan view of the piston head.

Referring to the drawings, the numeral 1 35 designates a hollow cylindrical container having a closed head 2 and a detachable end 3.

Within the container 1 is a piston 4 which is detachably connected to the piston rod 5, 40 extending through a suitable stuffing box in the detachable end 3 of the container.

The container is filled with air and a light non-congealable oil or its equivalent in such proportions that the volume of air therein is 45 equal to the displacement of the piston and piston rod when in the top of the container.

The container and piston are adapted to be connected to the frame and axle, respectively, of an automobile or the like by any 50 suitable means.

The piston 4 is provided with one or more fluid passages 6 extending therethrough which are enlarged at their lower ends to accommodate suitable check valves 7, opening 55 when the piston moves in an upward path and closing when the piston moves in a

downward path. Also, extending through the piston is one or more fluid by-passes 8, which are opened at all periods of operation, with the exception of the period hereinafter 60 described.

Supported from the head 2 of the container and within same, is the plate 9, which is designed to close the openings 6 and 8 in the piston when the piston has moved in a 65 suitable distance toward the container head.

The plate 9 is resiliently supported from the container head by an expansion spring 10, one end of which engages the bent up fingers 11 of the plate 9 and the other end 70 encircles the narrow neck of the downwardly projecting stud 12, made integral with the container head.

Assuming the parts to be in position as shown in Figure 1, and a short movement of 75 the body takes place, causing the piston to move toward the container head when this movement takes place, the valves 7 open, allowing the fluid to pass through the passages 6, thus permitting the piston to move 80 unrestrained. When the reaction of the vehicle springs takes place, the valves in the piston automatically close, holding the vehicle springs, in suspension, but allowing them to gradually reach their normal position as the 85 fluid flows past the piston through the by-passes 8.

When a long movement occurs, the piston moves the same as it did in the short movement, but in this instance it continues unrestrained in its movement until it strikes the plate 9, which closes all passages within the piston. Further movement of the piston compresses the air within the container, thereby reducing the shock, and at the same 95 time severely restraining its movement. When reaction of the vehicle springs takes place the action is the same as described in the short movement.

From the foregoing, it will be apparent 100 that I have shown and described one specific form of my invention, but it is to be understood that I do not limit myself to the precise details of construction, as modifications and variations may be made therein 105 without departing from the spirit of the invention.

Having thus fully described my invention, what I claim as new, and desire to secure by Letters Patent, is:—

110 A shock-absorber, including a fluid container having therein a piston provided with

fluid passages, means for closing certain of said passages on the down stroke of the piston, a plate suspended within said container and provided with integral fingers engaging 5 its supporting means, said means comprising a coiled spring the other end of which engages a projection formed integral with the

container head, and said plate adapted to close all passages within the piston on the extended upward movement of the same. 10

In testimony that I claim the foregoing I have hereunto set my hand at Libertyville, in the county of Lake and State of Illinois.

ALBERT C. REE.
